UNITED STATES PATENT OFFICE.

MARJORY HUNTER, OF EDINBURGH, SCOTLAND, ASSIGNOR TO ROBERT RUSSELL COCKBURN, OF LEITH, SCOTLAND.

BULKHEAD FOR SHIPS, &c.

SPECIFICATION forming part of Letters Patent No. 608,047, dated July 26, 1898.

Application filed November 19, 1897. Serial No. 659,068. (No model.)

To all whom it may concern:

Be it known that I, MARJORY HUNTER, gentlewoman, a subject of the Queen of the United Kingdom of Great Britain and Ireland, residing at 11 Goldenacre Terrace, Edinburgh, in the county of Mid-Lothian, Scotland, have invented an Improved Bulkhead for Separating Material in Warehouses, Ships, or other Situations, of which the following is a specification.

10 This invention relates to an improved bulkhead for separating grain and other material in warehouses, ships, or other situations, and has for its object to provide a simple and efficient portable bulkhead which can be readily erected and held firmly in position during use and which when not in use can be readily taken down and stored into a small compass.

Figure 1 is an end view, and Fig. 2 a plan, showing a single bulkhead. Fig. 3 is an end 20 view, and Fig. 4 a plan, of a double bulkhead. Figs. 5 and 6 show modifications.

Referring to Figs. 1 and 2 of the said drawings, I employ horizontal sleepers A, which are placed at suitable intervals on the floor 25 of the space to be occupied by the material being dealt with. On the outer end of each of the sleepers A is a chock a, of hard wood, which may be secured to the sleeper by screws or other suitable means, and against the 30 chocks a are placed vertical standards B, the top ends of which are connected to the inside ends of the corresponding sleepers by tie-bars b, which are preferably made of steel and are provided with hooked or bent ends b', adapted to fit over the ends of the upright standards and the sleepers. The ties b are also preferably formed with a twist, as shown, so as to increase their strength. The boarding C, of 35 suitable length, breadth, and thickness, is placed against the standards B and is retained in position by the pressure of the material being dealt with, the weight of which material also provides fixity of base for the structure.

40 By the use of the tie-bars b it will be seen that no nails or screws are used in the erection of the bulkhead, so that it can be erected and taken down with ease.

45 Figs. 2 and 3 of the drawings illustrate a double bulkhead which is constructed in a similar way to that first described, with the

exception that the sleepers A are made twice the length and are provided with two upright standards B, the boarding C being placed between same.

55

I may also arrange the sleepers and provide chocks where necessary to enable two bulkheads to be placed at right angles to each other, or I may arrange them so that a square may be formed; also, instead of securing a 60 wooden chock upon the outer end of the sleeper by screws or other suitable means I may, as indicated in Fig. 5, make this chock as part of an iron or other metal casting a', which is secured to the end of the sleeper by 65 any convenient means, such as by a screw or screws or bolts 3. The said casting has an upper projection to form the chock for the foot of the vertical standards to bear against, and the sole 2 of the casting is made nearly flush 70 with the bottom of the sleeper, except that the said sole is roughened or cast with diamond or other shaped projections for the purpose of causing the casting to grip into the floor and so make the sleeper very firm. 75 Without the said roughened sole the sleeper has to be a certain length in order to obtain the necessary hold upon the floor, whereas by the use of my said roughened sole-piece the length of the sleeper may be considerably reduced, thus reducing the cost, with greater 80 efficiency.

As a modification the roughened sole-piece may, as shown in Fig. 6, simply be a cast-iron or other plate 4, let into the under side of the 85 sleeper, the said plate being roughened in any convenient manner, so as to grip the floor, and secured to the sleepers by screws or other convenient means.

A further improvement shown in Fig. 6 90 consists in providing a second tie-bar 5 for the purpose of assisting in keeping the standards upright, this second tie-bar being a desideratum when an extra height of standard is employed. In this case I connect the one 95 end of the second tie-bar 5, by suitable detachable fastenings, such as a hook and eye, to the center of the length of the standards, the other end of the second tie-bar being connected to the end of the sleeper or to another 100 point in its length.

It will be seen from the foregoing that quad-

rangular bins may thus be formed in ships' holds for the purpose of keeping separate and distinct different parcels of bulk goods—such as grain, salt, ore, &c. When a bin is filled, 5 it can be sheeted over and other large bulk put on top of and surrounding the bin.

I claim—

1. A portable bulkhead for separating grain and other material in warehouses, consisting 10 of horizontal sleepers, provided with chocks at one end, vertical stands resting on said horizontal sleepers and against said chocks, tie-bars having bent ends engaging over the ends of the sleepers and vertical standards, and

boarding placed against the vertical stand- 15 ards.

2. A portable bulkhead comprising horizontal sleepers provided with chocks and roughened metal sole - pieces, vertical standards resting upon said sleepers and against said 20 chocks, boarding placed against said vertical standards, and the metal tie-bars having bent ends engaging over the ends of the sleepers and vertical standards.

MARJORY HUNTER.
